Application February 8, 1954, Serial No. 28,895

Term of patent 3½ years

(Cl. D15—1)

To all whom it may concern:

Be it known that we, Robert Goldman and Roy R. Nemzer, both citizens of the United States and residents of South Hempstead, in the county of Nassau, State of New York, have invented a new, original, and ornamental Design for a Child's Combination Stepladder and Stool, of which the following is a specification, reference being had to the accompanying drawing, forming a part thereof, and of which:

Fig. 1 is a perspective view of a child's combination stepladder and stool showing our new design.

Fig. 2 is a right side elevational view of our new design shown in Fig. 1.

Fig. 3 is a front elevational view thereof; and

Fig. 4 is a left side elevational view with the first step

swung into an elevated position to form a backrest for the stool.

We claim:

The ornamental design for a child's combination stepladder and stool, as shown.
